CLAIM

The ornamental design for a bipod, as shown and described.

DESCRIPTION

FIG. 1 is a left, front, top perspective view of the bipod in a deployed state;

FIG. 2 is a left, front, bottom perspective view of the bipod;

FIG. 3 is a rear elevation view of the bipod;

FIG. 4 is a front elevation view of the bipod;

FIG. 5 is a left elevation view of the bipod;

FIG. 6 is a right elevation view of the bipod;

FIG. 7 is a top view of the bipod;

FIG. 8 is a bottom view of the bipod; and,

FIG. 9 is a right, rear, top perspective view of the bipod in a folded state.

The shade lines in the Figures show contour and not surface ornamentation.

The broken lines showing portions of the design in all figures are included for the purpose of illustrating environment and do not form a part of the claimed design.

1 Claim, 9 Drawing Sheets
